UNITED STATES PATENT OFFICE

153,016

DESIGN FOR A LIGHT

Winfred O. Perry, Montclair, N. J., assignor to
Perry Products, Inc., Kenilworth, N. J., a cor-
poration of New Jersey

Application February 13, 1948, Serial No. 144,459

Term of patent 14 years

(Cl. D48—20)

To all whom it may concern:

Be it known that I, Winfred O. Perry, a citizen of the United States and a resident of Montclair, in the county of Essex and State of New Jersey, have invented a new, original, and ornamental Design for Light, of which the following is a specification, reference being had to the accompanying drawing, forming part thereof.

The figure of the drawing is a perspective view of a light, showing my new design.

The side of the light opposite to that shown in the drawing is the same as the side that is shown in the drawing.

I claim:

The ornamental design for a light, substan-
tially as shown and described.

WINFRED O. PERRY.
